REFRIGERATOR

Chester K. Litman, Kansas City, Mo., assignor to Koch
Refrigerators, Inc., Kansas City, Mo., a corporation
of Missouri

Application February 7, 1957, Serial No. 44,784

Term of patent 14 years

(Cl. D67—3)

Fig. 1 is a perspective view of a refrigerator showing my new design.

Fig. 2 is a front elevational view thereof on a reduced scale.

Fig. 3 is a side elevational view thereof on the same scale as Fig. 2.

Fig. 4 is a plan view thereof also on the same scale as Fig. 2.

I claim:

The ornamental design for a refrigerator, as shown.
